UNITED STATES PATENT OFFICE.

JOHN D. R. LAMSON, OF TOLEDO, OHIO.

PENCIL.

No. 903,873.

Specification of Letters Patent.

Patented Nov. 17, 1908.

Application filed February 6, 1908. Serial No. 414,545.

To all whom it may concern:

Be it known that I, JOHN D. R. LAMSON, a citizen of the United States of America, residing at Toledo, in the county of Lucas, 5 and State of Ohio, have invented certain new and useful Improvements in Pencils, of which the following is a specification, reference being had therein to the accompanying drawings.

10 This invention relates to improvements in pencils for holding detachable lead crayons and more especially to that class of pencils shown and described in my Letters Patent of the United States, one dated November 15 22, 1904 and numbered 775,493 and one dated May 21, 1907 and numbered 853,983.

15 The object of this invention is to provide a pencil of the class described, with cheap and efficient means for holding, projecting 20 and retracting the crayon and also with certain other new and useful features in the construction, arrangement and combination of parts, all as hereinafter more fully described and particularly pointed out in the 25 claims, reference being had to the accompanying drawing in which

Figure 1 is an enlarged axial longitudinal section of a device embodying the invention; Fig. 2, a further enlarged transverse section 30 on the line $x-x$ of Fig. 1; Fig. 3, a similar section on the line $y-y$; Fig. 4, a section on the line $z-z$; and Fig. 5 is a longitudinal section similar to that of Fig. 1, showing a crayon in place and illustrating 35 the manner of operating the crayon slide.

As shown in the drawing, a sheet of metal is rolled to form the cylindrical body or barrel 1 of the pencil having a longitudinal slot in one side, the edges of the slot being 40 inturned along the slot. The edge 2 at one side of the slot is notched to form a series of teeth 3 and the metal at the other side of the slot forms an inwardly extending wall 4 and at the axis of the body is rolled 45 into a tube 5 with a slot adjacent to the wall and opposite the slot in the body. A conical end 6 formed of sheet metal is secured to one end of the body in any suitable manner and an extension 7 of the tube 5 projects into an opening in the apex of the 50 conical point.

To firmly hold a crayon in the crayon tube 5 and provide means for projecting and retracting the same, a slide 8 is provided in

the tube and extends outward, through the 55 slot in the body. This slide is preferably a sheet metal stamping formed with an upper longitudinally extending spring-arm 9 having a lug 10 near its free end projecting outward through the slot in the body of the pencil, 60 and also formed with a lug 11 at its free end formed by bending the end of the arm laterally. A lower spring-arm 12 is adapted to engage and slide within the crayon tube and the free end of this arm is formed with a 65 longitudinally extending hook 13, the inclined end of which hook is above the plane of the lower edge of said arm 12 and at the base of the hook is a shoulder 14 so that when the crayon 15 is forced into the crayon 70 tube through the conical end, the inner end of the crayon will be forced beneath hook and abut against the shoulder. The hook is formed with a sharp point so that when the crayon is forced beneath said point it will 75 indent the crayon sufficiently to firmly hold it from becoming detached and dropping out. If desired, a notch may be provided in the crayon for the point of the hook to engage.

In writing, a pressure is applied to the 80 outer end of the crayon which tends to force said crayon back into the tube. This end thrust is taken by the shoulder 14 which the inner end of the crayon engages and the slide is prevented from being forced rearwardly by the engagement of its lug 11 with the teeth 3 on the body, these teeth being 85 formed with a straight side to engage the lug and prevent rearward moving of the slide and with an inclined side to permit free 90 forward movement. A lug 16 projects laterally from that portion of the slide which connects its two spring-arms, to prevent said slide from being tilted by the end thrust of the crayon, and the firm engagement of the 95 lug 11 at the opposite end of the slide with its teeth is insured by the spring action of said arms.

As illustrated in Fig. 5, by pressing inward 100 upon the lug 10, the arm 9 is depressed, disengaging its lug from the teeth on the body, and permitting the free movement of the slide in either direction along the crayon tube to project or retract the crayon. The slide and crayon may be removed from the 105 body by taking off the eraser cap 17 and sliding them out through the open rear end of the body, or the crayon may be quickly

released from the slide by running said slide forward until its hook reaches the end of the slot in the crayon tube, when the incline of the hook will engage the extension 7 of the tube and the hook will be raised thereby out of engagement with the crayon.

The eraser cap 17 consists of a tubular metal body 18 of a size to slip closely over the rear end of the pencil body and having an eraser 19 of any suitable material secured in its open end. In the side of the body 18 is a longitudinally extending depression or groove 20 formed with a roughened or corrugated bottom 21 forming an abrasive surface. This depressed portion 20 of the cap enters the longitudinal slot in the body of the pencil when said cap is slipped on, or the end of the body may be cut away to receive the depression. The point of the crayon is sharpened by removing the cap, placing the end of the crayon in the groove, and moving the crayon back and forth in contact with the abrasive surface until the lead is cut away to the desired point.

Having thus fully described the invention what I claim is:

1. In a pencil, the combination with a body and a crayon-tube in said body, of a slide within the tube formed with means for engaging and holding a crayon, said means being provided with a slanting surface adapted to engage the end of a crayon forced into said tube to raise said means into engagement with the crayon.

2. In a pencil, the combination with a body and a crayon-tube in said body, of a slide, a spring-arm on said slide within the tube formed with means for engaging the crayon and with a slanting surface at its free end adapted to engage the end of a crayon forced into the tube to flex the arm and raise said means into engagement with the crayon.

3. In a pencil, the combination with a body having a longitudinal slot and a crayon-tube in the body having a longitudinal slot opposite the slot in the body, of a member having opposing spring-arms adapted to be interposed between the body and a crayon in the tube, one of said arms engaging the body at its free end and the other engaging the upper side of the crayon at its free end and means on the arm engaging the body, which means project through the slot therein.

4. In a pencil, the combination with a cylindrical body having a longitudinal slot, and a crayon-tube in the body having a slot opposite the slot in the body, of an inturned edge on the body along one side of the slot formed with a series of teeth, and a member movable in said slots and consisting of longitudinally extending spring-arms united at one end, the upper arm engaging the teeth

at its free end and provided with a projection extending through the slot in the body, and the lower arm engaging the upper side of a crayon within the crayon-tube at its free end.

5. In a pencil, the combination with a cylindrical body formed of sheet metal and having a longitudinal slot and a crayon-tube in the axis of the body having a slot opposite the slot in the body, of a series of teeth formed on the body by turning the edge of the metal at one side of the slot inward and cutting notches therein, and a member consisting of parallel spring-arms, the upper one of which has its free end bent laterally to engage the said teeth and is provided with a lug projecting through the slot in the body and the lower arm is provided at its free end with a projection to engage the upper side of a crayon in the crayon-tube.

6. In a pencil, the combination with a body having a slot, and a crayon tube in said body having a slot opposite the slot in the body, of a slide movable in the tube and extending outward through the slot in the body, a spring-arm on the slide within the tube, a hook on the free end of the spring-arm formed with a slanting forward end adapted to engage the end of the slot in the tube and be lifted thereby to release a crayon, and means for holding the slide in the position to which it is moved along the slot.

7. In a pencil, the combination with a body having a slot and a crayon tube in the body having a slot opposite the slot in the body, of a slide movable in the tube, a longitudinally extending spring-arm on the slide within the tube, a hook on the free end of said arm to engage and hold a crayon, a shoulder on the arm at the base of the hook to form an abutment for the end of the crayon, and means for holding the slide against the end thrust of the crayon.

8. In a pencil, the combination of a body formed of sheet metal with a longitudinal slot, a series of teeth on the body along the slot, a crayon tube in the body having a slot opposite the slot in the body, a slide consisting of two longitudinally extending spring-arms connected at one end, one of said arms being adapted to lie within the tube, a hook on the free end of the arm within the tube to engage and hold a crayon, a shoulder on said arm at the base of the hook, a lug on the upper arm projecting through the slot in the body, a lug on the free end of said arm to engage the teeth on the body, and a laterally extending lug on the end of the slide opposite that on which the hook is formed.

9. In a pencil, the combination with a body formed of sheet metal with an open end, of a cap adapted to fit over and close

said end of the body, and a groove in said cap having an inner abrasive surface.

10. In a pencil, the combination with a body formed of sheet metal with a longitudinal slot extending inward from its open end, of an eraser cap, and a longitudinal groove in said cap adapted to enter the slot when the cap is placed upon the end of the

body, the bottom of said groove being corrugated to form an abrasive surface.

In testimony whereof I affix my signature in presence of two witnesses.

JOHN D. R. LAMSON.
